UNITED STATES PATENT OFFICE

RAYMOND F. PRESCOTT, OF MILWAUKIE, OREGON

DESIGN FOR A FONT OF TYPE

Application filed March 2, 1931. Serial No. 38,901. Term of patent 14 years.

To all whom it may concern:

Be it known that I, RAYMOND F. PRESCOTT, a citizen of the United States, residing at 2114 6th Ave., Milwaukie, in the county of Clackamas and State of Oregon, have invented a new, original, ornamental Design for a Font of Type, of which the following is a specification.

Reference being had to the accompanying drawing, forming part thereof, the drawing is a plan view of letters of the alphabet showing my new design.

I claim:

The ornamental design for a font of type as shown.

RAYMOND F. PRESCOTT.
